UNITED STATES PATENT OFFICE.

JOHN W. DARLEY, JR., OF BALTIMORE, MARYLAND, ASSIGNOR TO ERNEST J. KNABE, JR.,
OF BALTIMORE, MARYLAND.

SELF-PLAYING GRAND PIANO.

No. 901,281.

Specification of Letters Patent.

Patented Oct. 13, 1908.

Application filed July 9, 1906. Serial No. 325,409.

To all whom it may concern:

Be it known that I, JOHN W. DARLEY, Jr., a citizen of the United States, residing at Baltimore city, in the State of Maryland, have invented certain new and useful Improvements in Self-Playing Grand Pianos; and I do hereby declare the following to be a full, clear, and exact description of the invention, such as will enable others skilled in the art to 10 which it appertains to make and use the same.

My invention relates to improvements in self-playing grand pianos, that may be operated either by pneumatic means, or by 15 hand, or both, as desired.

The object of my invention is to produce a grand piano capable of being operated by pneumatic action, or by hand, and one that is compact in structure, keeping the generally accepted form of a grand piano, and 20 easily operated.

With this object in view, my invention consists in the construction and combinations of parts as hereinafter described and claimed.

In the accompanying drawings, Figure 1 is a side view of a grand piano embodying my invention. Fig. 2 is a front view of the same, some of the interior mechanism being shown in dotted lines. Fig. 3 is a top plan 25 view of the front part of the piano with the lid and the top of the casing removed. Fig. 4 is a vertical central section of the front of the piano, parts being shown in full lines. Fig. 5 is a top plan view of one end of the pneumatic box or action case. Fig. 6 is a 30 front elevation of the same. Fig. 7 is an end view of said box with the end removed. Fig. 8 is an end view of the casing inclosing the bellows, the rerolling and tempo mechanism, 35 the operating handles and showing the spring joint of the air ducts. Fig. 9 is another end view of the casing shown in Fig. 8, the spring joint being omitted. Fig. 10 is a 40 vertical section on the line 10—10 of Fig. 3, looking opposite to the direction of the arrows. Fig. 11 is a section on the same line, looking in the direction of the arrows. Fig. 45 12 is a vertical section on the line 12—12 of Fig. 3, looking in the direction of the arrows. Fig. 13 is a section on the line 13—13 50 of Fig. 3. Fig. 14 is a side view of the motor of Fig. 3. Fig. 15 is a side view of the governor and gate box. Fig. 16 is a side view of the folding means for holding up the front of the piano. Fig. 17 is a top plan 55 view of the same. Fig. 18 is a front view, on

a small scale, showing how the lid of the piano is raised and supported. Fig. 18 is a side view of the same. Fig. 19 shows the arrangement of the pneumatic pedals and their connections. Fig. 20 shows the left leg and 60 supporting casting therein, and Fig. 21 is a cross section of the same. Fig. 22 shows the connection between some of the parts.

a represents the casing of a grand piano provided with a hinged lid b, the front part 65 of which lid, c, is also hinged to the rear lid, and the supporting legs d, these parts being of the usual construction. The piano is also provided with the usual sounding board e, ordinary pivoted keys f, and any approved 70 type of piano action g. It is also provided with the usual lyre h, in which are carried the ordinary pedals i and j. Underneath the folding parts c of the lid is arranged the box k, in which the music rolls are placed. This 75 box is provided with a cover m, hinged at n, and having a front o hinged to the cover m, so that it may fold entirely back, as shown in the horizontal dotted lines in Fig. 11, or may be folded up to form a music rest, as 80 shown in inclined dotted lines, Fig. 11, p representing rubber buffers to keep the parts from being scratched or marred. Small pins p¹ projecting from the upper casing pass into 85 holes in the front o, when it is in the inclined position and retain it in place.

Within the box k are located the music rolls r and s, and the tracker board t connected by tubes u with the pneumatic portion of the apparatus. The box k, containing the music rolls, is only the front part of a larger box v, a partition w separating the music roll portion from the box proper. This box contains the tubes u, already referred to, leading to the tracker board. 90 These tubes all run backward and pass into a header x, and this large box v is hinged at y to the piano case, so that the entire box v can fold backward about the hinges y when the lid is open; so that access may be had to 100 the tuning pins 1 for tuning the strings.

The pneumatic tubes u converge together and run over a plate in the central part of the box v; in the rear of this box, and underneath the sides of the tubes are the pumpers 3. These pumpers are provided with discharge openings 4, and movable covers 6 controlled by springs 5 located over said openings, similar suction openings 4 being, of course, provided at the bottom of the 110

pumpers. Springs 7 attached to the top of the box, and to the top of the pumpers normally keep the pumpers closed, and by the use of the pedals the movable members of 5 said pumpers are lifted against the tension of said springs, as hereinafter described, each of said pumpers being provided with an extension 11 for that purpose.

The air passes to the pumpers through a 10 passage 8 in the coupling member 9, which coupling member is provided with a facing 10 of leather, felt or similar material to prevent the air from escaping. The air passage 12 leads into the air trunk 13, the ends 15 of the passages 8 and 12 simply fitting against each other. To insure a tight fit, I have provided the means shown in Fig. 8, in which 14 represents a flange on the end of the trunk 13, and 15 another flange part 20 allel thereto connected therewith by means of screws 16. Springs 17° tend to press the coupling member 15 against the coupling member 9. The portion 18° of the walls of the passage 12 is made flexible so as to permit of the movement of the coupling member 15, that when the box *v* is folded down into the position shown in Fig. 8, which is its normal position, a tight joint will be formed between the coupling members 9 25 and 15 by means of the packing 10.

The action of the pumpers 3 is to produce a partial vacuum in the pneumatic box 14, the air passing upward through the passage 13 into the pumpers as hereinafter described. 30 The air which passes outward into the box *v* passes out through the holes 15^a into the inside of the piano. The pneumatic box is shown in side elevation in Fig. 4, in top plan view in Fig. 5, and in Fig. 6 in front elevation with the front cover removed. The 35 pneumatic box 14 is in the main of the ordinary construction, but instead of having the valves, primary and secondary pneumatics, connecting passages and choking devices underneath the main pneumatics, which would make a very large and clumsy looking arrangement, I locate these behind the same, as shown in Fig. 7. This is of especial importance in a grand piano, as otherwise this 40 portion of the pneumatic apparatus would be too prominently displayed in the front and on the side.

The pneumatic box, choking devices, valves and passages, therefore, will not be 45 further described, as they are of the ordinary type. It may merely be said that the air, when a perforation in the music roll passes over one of the ends of the tubes *u* in the tracker board, is sucked in through 50 the tubes *u* and passes down through the tubes 29 and 16 connecting therewith, and by the valves and passages shown in Fig. 7 55 communicates with the interior of the pneumatic box in the usual way.

60 65 To removably secure the pneumatic box in

position on the piano frame, I provide two ribs 17^a on the front and upper edge thereof, which fit into correspondingly shaped recesses 18^a in the part 19, which is screwed or otherwise secured to the key bottom 20. 70 The rear of the box is secured to the key bottom by screws 21, passing through holes 22, and at the other rear corner by a screw passing through a casting 23, secured to the box 14 shown in Fig. 4. 75

The tubes 29 pass into a header 24, Fig. 4, located immediately beneath the header *x*, the tubes *u* and 29, of course, registering with each other, and a packing being provided between the headers 24 and *x*. Similarly the lower ends of the tubes 29 pass into a header 25, which is adjustably secured to the key bottom 20, by means of screws 26, which pass through slots in the header. The header 25 is just over the corresponding 80 header 27, which is attached thereto by screws 28, an air excluding packing being located between the headers. In fact whenever necessary, packing is used. The tubes 16 pass into the header 27, and their ends 90 register with the ends of the tubes 29. The header 27 is of about the same length as the header *x*, and is located nearly underneath it. The header 25 is located directly above the header 27, and the pipes 29 diverge, half 95 towards each side, and pass upward near the sides of the piano, as shown in dotted lines in Fig. 3, and then converge again into the header 24, being then contained in a box 30 located immediately underneath the 100 header 24.

In building a self-playing piano it is, of course, highly desirable not to increase the length or width of a commonly employed frame, as this would involve considerable 105 extra expense. Provision must therefore be made for an extra amount of room on the left to accommodate the left hand end of the pneumatic box in order to afford space for the operation of the pneumatically operated levers, which actuate the piano action. Provision is shown for this extra space in Figs. 20 and 21. 110

A metal casting 31 is provided for the reception of the left hand end of the pneumatic box, and the left hand leg *d* is built up around this casting, as shown in Fig. 20. This casting 31 is provided with a downwardly projecting pin 32, which projects into a corresponding depression in the leg *d*. 115 Screws 33 pass through the casting 31 into the piano leg in various positions, as shown in Fig. 20. The casting 31 is provided with lugs 34, which dove-tail into a metal plate (not shown) let into the bottom of the piano, 120 and a screw 35, which passes through a hole 36 is the leg *d*, then secures the leg in position with the casting therein, the leg *d* the casting being, of course, removable, for the purpose of shipment. This gives an extra 125 130

space on the left hand end of the piano into which the left hand end of the pneumatic box may be slipped, and providing means for its easy removal. The right hand and 5 the rear legs are secured in place by dovetails and screws in the usual manner.

The key bottom 20 is cut away, as shown at 37, to afford clearance space 37. This is necessary for the accommodation of the parts 10 which actuate the piano action, but this clearance space 37 is extended to the rear in order to afford space for the easy removal of the pneumatic box 14 and the parts connected thereto.

15 One object of my invention is to economize space, and preserve the ordinary attractive appearance of a grand piano. To this end it is necessary to economize every available inch of space, and in Figs. 3 and 4 is shown 20 an arrangement made with this end in view. The pipes *u*, as shown in Fig. 3, converge from the header *x* into a small space, being supported by the board 2. The tubes *u* thence curve down and around the curved 25 partition *w* above which is located the spool. The board 2 is provided with side flanges 38, which serve to keep the tubes *u* in place, and which pass forward and form the sides of the box portion in which the music rolls are 30 placed.

39 is the motor for driving the music roll, or spool, which is of the usual construction, and which operates to unroll or reroll the music in the usual way. Sometimes it is desirable to use narrow sheets of music. This 35 would necessitate closing up the extra holes in the tracker board, but I prefer to render said holes inoperative by the means shown in Figs. 3 and 12.

40 The tubes on the outer ends of the header *x*, a few on each side, instead of communicating directly with the tracker board, are bent, as shown at 40, in Fig. 12, and run into a header 41, which is secured to one of 45 the side flanges 38 by the angle iron 42. These tubes coming from the header *x* are shown at 45. To the header 41 is slidably attached a sliding valve 43 provided with 50 grooves for establishing communication between each of the pipes 44 and the corresponding pipe 45, and for terminating said communication when desired to operate with a narrow roll of music. This device being 55 old and well known in the art will not be further illustrated or described.

When the valve 43 is open each of the tubes 45 communicates through it with one of the tubes 44, which latter lead to a corresponding hole on the tracker board; thus by 60 closing the valves 43, a few holes on each end of the tracker board can be rendered inoperative.

Extending entirely underneath the pumpers 3 is an air trunk 48, into which the air 65 is delivered through the passage 8, as al-

ready described, and from which it passes into the pumpers 3. From this trunk a connecting trunk 49, shown in section in Fig. 13, leads into the equalizer 50 through the aperture 51. A spring 52, which has a tendency to keep the vacuum in all parts of the apparatus connected with the air trunk at a substantially constant pressure, is provided. 70

The operation of the motor governor and controlling handles therefor, will next be 75 described. In the position shown in Fig. 3, the parts are arranged for rerolling. Referring to Fig. 12, 53 represents a vertical partition or septum, through which passes an air duct 54, which leads from the air 80 trunk 49 to the chamber 55, shown in dotted lines in Fig. 3, to which the air passes freely through the opening 56 from the box 57, into which it comes through the duct 58 from the air trunk 59, and through the latter 85 from the air duct 60 from the motor 39. Under rerolling conditions there is a free 90 passage for the air in the course just named to the air trunk 49 from the motor 39, it being understood, of course, that said motor 95 is a vacuum motor. A valve 61 is provided for the purpose of closing the opening 56, but in the act of rerolling this valve is held open, as shown in Fig. 3, by the following means. To the rerolling handle 62 is connected 95 a rod 63, the end of which is slidably supported in the block 64 attached to the base of the box *v*. This rod carries a bent arm 65, which operates by a rod or wire 66 on the valve 61, and in the position shown 100 in Fig. 3 everything is ready for rerolling. In the playing position the handle 62 is moved to the right, whereupon the valve 61 closes the opening 56, thus constraining the air to pass through the regulator valve and 105 the tempo valve. The rod 63 also extends over to the left of the box *k*, and its end is pivoted to a lever 67, the other end of which is pivoted at 68 to a part of the box *v*. This 110 lever is provided with a pin 69, which engages with the shifting mechanism 70, so as to shift the clutch mechanism to the rolling or rerolling position in the usual manner. At the rear of the lever 67 it carries a projecting portion forming a bell crank, which 115 bell crank portion is provided with an upwardly extending pin 71. On the top of the pin 71 is pivoted a link 72, which passes loosely through the holes in the brake levers 73 and 74, which are pivoted in the forked 120 bearings 75 and 76, secured to the box *v*. These levers carry brake shoes 77 and 78, adapted to press against the brake drums 79 and 80 attached respectively to the spindle of the spool and the chuck of the music roll. 125 Each of the brake levers 73 and 74 is kept in position on the link 72 by means of pins 81, and springs 82.

It is obvious from the construction shown, see especially Fig. 11, that when the link 130

72 is moved in one direction, as for rerolling, the brake lever 74 will be moved by one of the pins 81 so as to disengage the brake shoe 78 from the part 80, thus allowing the music roll to revolve freely while one of the springs 82 will bring the friction upon the drum 79, thus keeping the paper taut. The reverse, of course, is true when the handle 62 is shifted to the playing position.

10 Of course, while the rerolling is going on, it is essential that the connection between the air trunk 48 and the pneumatic box should be cut off in order to prevent the playing during the rerolling, and this is accomplished in the following manner. The rod 63 has pivoted to its right hand end a link 83, Fig. 2, and the other end of this link is pivotally mounted in a block 84 on one end of the lever 85 pivoted on the inside of the right hand end of the box *v*, at 86. The other end of this lever is provided with a link 87, which extends through a bushed hole in the top of the air trunk 48, immediately over a valve 88. The valve 88 is pivoted, as shown at 89, and a spring (not shown) normally holds said valve up against the lower end of the link 87. In other words, when the link is up in the position shown in Fig. 9, the valve 88 is closed.

20 To shift from the rerolling to the playing position, the handle 62 is moved to the right from the position shown in Fig. 3. This action forces the link 87 down against the valve 88 opening it, at the same time swinging the lever 67 from the rerolling position to the playing position, and shifting the position of the brake shoes 77 and 78. It also shifts the clutch mechanism so that the action of the motor drives the spool instead of 30 the music roll. At the same time the arm 65 is moved to the right allowing the wire 66 to move in the same direction, whereupon the valve 61 closes the opening 56 by means of the spring attached thereto. The air 35 then coming in through the trunks 60 and 59 passes through the passage 58 into the chamber 57, in which is located the tempo valve through the port of which the air passes into the motor governor 90, shown in Fig. 14.

40 The spring bearing against the valve 88 by the connections described would naturally tend to throw the rod 63 over into the position shown in Fig. 3. To counteract this tendency, the parts are so arranged that 45 when the rod 63 is moved over to the right, it carries the lower end of the link 83 beyond the pivotal point of the block into which the upper end of the link 83 passes, so that in that position the tendency of the 50 spring would be to hold the handle 62 in the playing position.

50 In the bottom of the chamber 57 is located the tempo valve 91, and a spring 92 normally holds said tempo valve against the

bottom of the chamber. A slot 93 is cut in 65 the bottom of the chamber 57, more or less of which is covered by the tempo valve, according to its position. It is evident that the smaller the hole the more resistance the air will meet as it passes through said tempo 70 valve port, and consequently the higher the pressure will be in the air trunk 59, and the slower the motion of the music spool will be. The tempo valve is regulated in its position by means of a wire or rod 94 connected to 75 an arm 95, which in turn is connected to a rod 96 terminating in a handle 97 moving over a graduated scale 98 at the front of the piano. The other end of the wire or rod 96 passes through a bearing in the block 64, and 80 said wire or rod also has a bearing in the side piece 38.

The handles 62 and 97, the connection between them, and the operating parts already described, are located within the box *v*, 85 which, as before said, may be folded back. This makes the connections much more simple, and as these handles are only operated when a new piece of music is to be inserted into the piano, it is not necessary that they 90 should be located near the handles, which are necessary in the ordinary playing of the piano.

Referring now to Fig. 14, the bottom of the motor governor 90 has a hinged bottom 95 100 and flexible sides 101, and a flexible end 102, a spring 103 tending to keep the bottom 100 normally in the position shown in Fig. 14. The tension of the spring 103 may be adjusted by means of the screw 104, and this spring 103 normally tends to throw the bottom down, while the pressure of the external air, when there is a partial vacuum inside of the governor, tends to throw it up. To the bottom 100 is pivotally attached a 105 link 105, the upper end of which is pivotally connected to a hinged valve 106, which governs the degree of pressure of the partial vacuum inside the motor governor, keeping it practically constant, the valve 106 moving rapidly up and down according as the pressure varies in the main air trunk. The air during the playing passes from the motor through trunks 59 and 60 and the port 58 into the box 57, through the slot 93 110 governed by the tempo valve 91, into the regulator bellows or governor 90; then through the port 107, governed by the regulating valve 106 into the box 55, and thence to the conduits 54 and 49 on to the main exhaust. I have provided separate means for 115 the purpose of phrasing, positively operating in both directions on the movable bottom 100 of the motor governor. These means are as follows:—Pivoted in a recess 120 in the front of the key bottom of the piano is a vibratory lever 108, which is centrally pivoted and is provided with a depending

125

link 109, the lower end of which is connected to the upturned end of a bent lever 110, which is nearly concealed in a recess cut in the front portion of the key bottom. The lever 110 after being bent downwardly and backwardly, as shown in Fig. 4, has a horizontal portion 111, bent at right angles to the plane of the lever portion, and to the other end of this portion 111 is a rearwardly extending portion 112, Fig. 4, the inner end of which is pivoted to an upwardly extending link 113. The upper end of the link 113 is pivotally connected to a lever 114, which is mounted on a screw 115 on the inside of the right hand portion of the casing of the piano. This screw or pivot pin 115 is concentric with the shaft 116, which passes in nearly to the part 38, it then being bent forward and terminating in a right angled portion 118, which is connected by a link 117 to the bottom of the motor governor 90. The shaft 116 is mounted in brackets 119, on the septum 53, one of these being shown in Fig. 8. The movement of the rod 113 causes a rocking movement of the shaft 116 in the following manner. Keyed to the shaft 116 is a horizontal arm 120, the ends of which are provided with projecting pins 121 and 122. These pins rest upon portions cut out from the lever 114, so that the movement of the link 113 either up or down will produce a corresponding movement of the arm 120, thereby partially rotating the shaft 116 either forward or backward.

The box *v* is pivotally mounted in the front of the piano case, and the pins 121 and 122 loosely rest upon the lever 114, so that as the box *v* is folded backwards to the position shown in Fig. 18, the arm 120 and lever 114 will separate from each other without disconnecting any of the parts. As previously stated the box *v* may be folded back so as to allow the tuner to reach the interior parts of the piano, and when folded back it assumes the position shown in Fig. 18. In Fig. 17 is shown the means for securing the piano lid in position when it is folded back. A brace or stick 123 is pivoted in the top of the piano frame and is adapted to rest in a socket 124 on the underside of the lid, as shown in dotted lines in Fig. 17. In a cut away portion of the stick 123 is pivoted a wire 125 having a hooked end 126 adapted to fit in a hole in the pocket 124.

Under ordinary conditions the wire is folded down, as shown in Figs. 15 and 16. When, however, it is desired to throw the piano lid back as far as possible, in order to provide room for the lifting of the box *v*, the rod 125 is swung outwards and the hooked end thereof engaged in the hole in the socket 124, as shown in full lines in Fig. 17. The box *v*, however, is, under ordinary conditions, locked down in the position shown in Figs.

3 and 4, by means of pivoted latches 127 65 pressed outward by springs 128, the latch on the right hand side of Fig. 2 being omitted. The latches have their tops projecting outward, and engaging castings of brass, or other metal 129, let into recesses in 70 the casing of the piano. Each of these castings has a cut away portion 130 large enough to admit a finger. The latches are prevented from being driven by the springs 128 too far outward by means of pins 131 securely 75 fastened therein, which are longer than the width of the slots in the box *v*, in which slots said latches move freely. The upper part of the latches 127 is flush with the tops 80 of the castings 129, which castings are cut 85 away, as shown at 130. By pressing the latches in sidewise, the box *v* is released and can be tilted backwards, but before that tilting action can be effected, the screws 132 in the header *x*, must be removed and also 90 the screws 133, which pass down through an extension of the air trunk, as shown at 134, into the top of a block, which is secured to the casing forming the air duct 13. I prefer, however, the construction shown in Fig. 8, 95 by means of which the box *v* can be folded back without the necessity of removing any screws, as the break takes place between the air ducts on the linings or packings 10 and 135.

In Fig. 8 is also shown means for preserving a tight joint where the parts meet in the neighborhood of the packing 135. The header 136 is movably attached to the rear 137 of the box by means of screws 138, 100 which pass loosely through holes in the header 136 and into the part 137, springs 139 surrounding said screws and normally keeping said header 136 in contact with the packing 135. As the box *v* is folded backward, the header 136 moves downward slightly until stopped by the screws 138, and similarly the bracket or block 15 moves upward slightly until stopped by the screws 110 16. When the box is folded down, the reverse action takes place, and a tight joint is thus maintained.

Referring to Fig. 4, means will be seen for adjusting the piano action relatively to the pneumatic apparatus. 140 represents 115 pushers, which pass through bushed holes in the key bottom, and which always remain in said bottom after having been placed there. Each of these pushers rests upon a felt washer 141, and is provided with 120 a felt cap 142, slightly above the top of which is the enlarged head of an adjusting screw 143, one of these being threaded through each of the keys *f*. Thus the piano action may be removed through the front of 125 the casing and the pneumatic box be removed from underneath the piano bottom without disturbing the pushers 140, and of

course the parts may be assembled by a reversal of this operation.

i represents the ordinary soft pedal, which operates to shift the keyboard laterally in 5 the usual manner.

j represents the loud pedal, which produces the usual effect in raising the dampers, but in the following manner. In other words, when the pedal *j* is depressed by the 10 operator, it lifts the rod 144, Fig. 4, which in turn pushes up the inner end of the lever 145, which is pivoted at 146 to a bracket secured to the key bottom. This depresses the other end of the lever 145, which in turn 15 presses one end of the lever 148 pivoted near its center at 149 to the inside of the right hand leg of the piano. The movement of the lever 148 in turn raises the rod 150, which passes through a bushed hole in 20 the piano bottom, and terminates under the rail 151, which extends horizontally under the damper levers 152, a packing of felt 153 being interposed, so that when the rod 150 is elevated, the dampers will be lifted from 25 the strings in the usual manner.

The pedal mechanism and the parts connected therewith will next be described.

The lyre *h* has on its rear side near the bottom thereof a bracket 154 provided with 30 bearings in which is mounted a shaft 155. 156 and 157 represent bent arms, the lower ends of which are mounted on said shaft, 158 representing bosses made integral with said arms 156 and 157 and secured to said 35 shaft by pins 159. The construction is substantially the same on both sides, and therefore only one will be described. The arm 157 has at its top a laterally extending cylindrical part 160 on which the pedal 161 40 is loosely mounted, a washer 162 keeping the pedal in place thereof. The washer 162 is arranged so that when the parts are folded down, as shown in Fig. 19, its flat portion will rest upon the floor, and the outer end 45 of the arm 157 is similarly shaped so as to afford a firm bearing on the floor. The pedal 161 is provided on its other end, as shown at the top in Fig. 2, with a hole for the reception of one end of a bent link 163, 50 the other end of said link passing through a hole in the end of a link 164, which in turn is pivoted in the forked end of the horizontal portion 166 of the lever 165. This lever is shown in side elevation in Figs. 4 and 19, and in front elevation in Fig. 2, and it consists of a horizontal portion 166 provided with a downwardly extending stop 167 and an angled portion 168, and a long power transmitting portion 169 arranged 55 at right angles to the parts 166 and 168. The part 169 is journaled at one end in a bracket 170, Fig. 4, which is bolted, or otherwise secured to the rear of the lyre and extends backward to about the center of the 60 pneumatic box 14. The outer end of said 65

portion 169 is pivoted in a bracket 171 screwed to the right leg. The part 168 of the lever 165 is provided with a horizontal extension 172, on the reduced portion of which a vertical rod 173 is fitted, being secured thereon by a pin 174. This rod extends up through the casing and contacts with the under part of the projection 11 on one of the pumpers.

The operating means for the left hand 75 pusher is substantially the same except that to the part 172 there is secured a bent rod, preferably of steel, 175, which rod, as shown in dotted lines in Fig. 2, passes first upward, then outward, then upward, then inward, 80 then upward again, and near its upper end is fastened to a block 176 having a felt cushion 177, which contacts with the under face of one of the pumpers. The rod 173 is similarly provided with a felt top or 85 cushion.

In the position shown in Fig. 2, the pedals are locked up, and the means for releasing them are best shown in Figs. 2, 4 and 19. 178 represents a key slip pivoted to the 90 front of the key bottom of the piano, and extending backwardly therefrom is a rod 179, the outer end of which is pivoted to said key slip, and the inner end of which is bent down, as shown at 180. The rod or 95 arm 179 is located at the left hand end of the piano, and the lower down turned end of this arm is pivoted to the upwardly extending arm 181 on the shaft 182, which runs across the front of the piano and terminates near the middle of the lyre in an outwardly projecting lever arm 183, the outer end of which is located immediately above the top of a vertical rod 184. The rod 182 is secured to the bottom thereof in 100 suitable bearings, one of which is shown at 185. The rod 184 is slideable in suitable bearings secured on the rear of the lyre, and terminates in its lower end in a hooked portion 186, which is adapted to be engaged 110 by a pin 187 secured in the shaft 155. Obviously, as long as the hook 186 engages the pin 187, the pedals cannot be folded down, but when the rod 184 is moved downwards this locking engagement is broken, and the 115 pedals are then positively forced outward by the tension of the spring 188, which is coiled around the shaft 155. A spring 189 normally keeps the rod 184 in its upper position, that is to say interlocked with the 120 pin 187.

The spring 188 performs two functions. As soon as the pedals are unlocked it forces them outwardly until the center of the bearing 160 is about in line vertically with the 125 center of the shaft 155. Gravity then acts upon the pedals drawing them down, and the spring then resists the action of gravity and allows the pedals to slowly drop to the floor in the position shown in Fig. 19. The 130

arm 156 is bent, as shown, in order to provide clearance around the inner end of the pedal 161, which connects with the link 163. The links 163 and 164 and the arm 156 have 5 their bearing points so arranged and operative lengths so proportioned, that the pedals will automatically move from the folded position shown in Fig. 4 to the operative position shown in Fig. 19, the loci of the 10 centers that move during this folding operation being shown by broken lines.

By the construction described, it is obvious that the depression of the pedals 161 will, through the connections described, operate the pumpers, thus operating the pneumatic portion of the piano. This skeleton form of construction of the pedals and their 15 location, as shown in Fig. 4, that is to say, practically under the pneumatic box, when 20 folded up, does not detract from the usual appearance of the piano.

On the bottom of the pneumatic box 14 is a block 190, and on the rear of the lyre is a similar block 191, said blocks being connected by an inclined brace 192 for the purpose of stiffening the structure and resisting the thrust of the operator's feet upon the 25 pedals.

Referring now to Figs. 2 and 7, 193 represents a depressible plunger working loosely 30 through a bushed hole in the front of the key bottom and operating through various levers and links upon the rod 194, which controls the choker valve 195 for the bass, 35 and a similar pusher 196 controls in a similar manner the choking valves for the treble, and the lever 197 is arranged to depress both of these plungers simultaneously, if desired. 198 represents a lever, which, is pivoted to 40 the framework of the piano, as at 198^b. The inner end of the lever 198 is connected by a link 198^c with the outer upper end of the lever 198^a, which is formed integral with the bearing portion 198^d, which is mounted 45 in bearing blocks 198^e. The bearing portion 198^d is bent at one end to form the lever 198^f and the latter is bent to form the portion 198^g, which extends over the outer end 147 of the lever 145. Hence when the 50 handle end of the lever 198 is pulled to the right in Fig. 2, the part 198^g depresses the outer end 147 of the lever 145, thereby lifting the dampers by a part of the means already described, so that the loud effect can 55 be produced either by hand or by foot.

While I have thus described my invention, I wish it to be distinctly understood that I do not limit myself to the exact details shown in the drawings and set forth in 60 the specification, but

What I claim is:—

1. In a self-playing grand piano, the combination with the frame, horizontal sounding board, key bed, and keys thereof, pumping mechanism secured and supported upon 65

the frame above the sounding board, a casing above the key bed a pneumatic motor for actuating the music rolls secured in said casing and provided with a controlling valve mechanism, pneumatic connections for the 70 said motor, and a tempo lever secured to said casing and connected to actuate said valve mechanism, substantially as described.

2. In a self-playing grand piano, the combination with the frame, horizontal sounding board, key-board, and keys thereof, pumping mechanism secured and supported upon the frame above the sounding board, a casing above the key bed a pneumatic motor for actuating the music rolls secured in said 75 casing, and provided with a controlling valve mechanism, pneumatic connections for the said motor, and means for alternating the music roll actuating connections of the said motor, and a controlling handle therefor 80 mounted in said casing, substantially as described.

3. A self-playing grand piano, having in combination with the string frame and piano keys thereof, a tracker board and music roll 90 mechanism a movable casing in which said mechanism is mounted, located above the said string frame, an actuating motor therefor, and controlling mechanism therefor, including a tempo lever mounted in said cas- 95 ing, substantially as described.

4. A self-playing grand piano, having in combination with a string frame and piano keys thereof, a tracker board and music roll 100 mechanism a movable casing in which said mechanism is mounted, located above the said string frame, an actuating motor therefor, controlling mechanism therefor, and means for reversing the movement of the rolls including a lever mounted in said cas- 105 ing, substantially as described.

5. A self-playing grand piano, having in combination with the string frame a motor for actuating the music rolls, a movable casing in which said rolls are mounted, located 110 above the said string frame, and controlling mechanism for the said motor mounted in said casing, substantially as described.

6. A self-playing grand piano, having in combination with the string frame a motor 115 for actuating the music rolls, a movable casing in which said rolls are mounted, located above the said string frame, and controlling mechanism for the said motor mounted in said casing including a manually operated handle mounted in said casing, 120 substantially as described.

7. A self-playing grand piano having in combination with the string frame a motor for actuating the music rolls, a movable casing in which said rolls are mounted, located 125 above the said string frame, and controlling mechanism for the said motor mounted in said casing, including a manually operated handle mounted in said casing, and means 130

- for alternating the driving connections from the said motor for reversing the actuation of the said music rolls, substantially as described.
5. 8. A self-playing grand piano, having in combination with a string frame a motor for actuating the music rolls, a movable casing in which said rolls are mounted, located above said string frame, controlling mechanism for the said motor mounted in said casing, including a manually operated handle mounted in said casing, and means for alternating the driving connections from the said motor for reversing the actuation of the said 10 music rolls, comprising a handle mounted in said casing, substantially as described.
9. A self-playing grand piano, having in combination with a string frame a pneumatic motor, a movable casing in which said 15 motor is mounted, located above the said string frame, music rolls mounted in said casing, connections from the said motor for actuating either one of the said music rolls, and manual means for controlling the said 20 connections mounted in said casing, substantially as described.
10. A self-playing grand piano, having in combination with the string frame a pneumatic motor, a movable casing in which said 25 motor is mounted, located above said string frame, music rolls mounted in said casing, connections from said motor for actuating either one of the said music rolls, manual means for controlling the said connections 30 mounted in said casing, and manual means for controlling the said motor mounted in said casing, substantially as described.
11. A self-playing grand piano, having in combination with a string frame a pneumatic motor, a movable casing in which said 35 motor is mounted, located above the said string frame, music rolls mounted in said casing, connections from the said motor for actuating either one of the music rolls, and 40 connections for controlling the said motor mounted in said casing, said connections including a handle extending to the front of said casing, substantially as described.
12. A self-playing grand piano, having a hinged casing above the sounding board containing the air trunk, pumps, motor, motor 45
- governor, equalizer, tracker bar, and music rolls, substantially as described.
13. In a self-playing grand piano, a string frame and a hinged casing containing pneumatic mechanism located above said string frame in combination with latches for retaining said casing in place, substantially as described. 55
14. A self-playing grand piano having a hinged casing above the sounding board containing the air trunk, substantially as described. 60
15. A self-playing grand piano having a hinged casing above the sounding board containing the pump, substantially as described. 65
16. A self-playing grand piano having a hinged casing above the sounding board containing the motor governor, substantially as described. 70
17. A self-playing grand piano having a hinged casing above the sounding board containing the equalizer, substantially as described.
18. In a self-playing grand piano, the combination of the pneumatic box with a valve chest located on the side of said pneumatic box, and chokers located under the valve chest, substantially as described. 75
19. In a self-playing grand piano, the combination of a hinged casing, a motor governor therein having a movable bottom, connections to the movable bottom of said governor, a phrasing lever, and means operated by the movement of said lever to actuate 80 said connections in one direction or the other according to the movement of the lever, said means being disconnected from said connections so that the casing may be freely folded back, substantially as described. 85
20. In a piano, a horizontally-disposed case and strings, a keyboard, and a winding-roll, a tracker and a music-sheet support mounted above said keyboard and said strings and overlying the front portion of the string-supporting frame. 90
